UNITED STATES PATENT OFFICE.

JAMES G. MACLAREN, OF MAMARONECK, NEW YORK.

GOVERNING MECHANISM FOR DESPATCH SYSTEMS.

1,354,116.

Specification of Letters Patent. Patented Sept. 28, 1920.

Application filed March 4, 1918. Serial No. 220,123.

To all whom it may concern:

Be it known that I, JAMES G. MACLAREN, a citizen of the United States, and resident of Mamaroneck, Westchester county, State 5 of New York, have invented an Improvement in Governing Mechanism for Despatch Systems, of which the following description, in connection with the accompanying drawings, is a specification, like characters on the 10 drawings representing like parts.

This invention relates to means for governing an electrically operated or electrically controlled mechanism in conjunction with the movement of traveling members 15 along given routes. As an example of the type of system with which it may be utilized, I have here chosen for illustration a pneumatic despatch system wherein carriers are despatched through transit tubes under 20 pneumatic pressure. Such systems are well known, one major field of use being the transmission of change and memoranda in stores and the like.

My invention is adapted for the government 25 of various mechanisms which it might be desired to operate in conjunction with such a system. For purposes of illustration I have shown an installation wherein the mechanism governed is an electric motor 30 driving an exhauster which provides suitable sub-atmospheric pressure in the transit tubes to move the carriers therethrough.

My invention will best be understood by 35 reference to the following description of a single illustrative embodiment thereof shown in the accompanying drawings wherein:

Figure is a general and partly diagrammatic view of the installation and constitutes a wiring diagram;

Figs. 2 and 3 are sections on the lines 2—2 and 3—3 of Fig. 1; and

Fig. 4 is a sectional view showing a type 45 of switch used in conjunction with the transit tubes.

Referring to Fig. 1 of the drawings, I have there shown my invention as applied to a pneumatic system operated by sub-atmospheric pressure or vacuum and have shown 50 two double tube vacuum lines, a long line containing a despatch tube 7 leading from the main terminal station at the left hand side of the figure to the branch station at the upper right hand side and a return tube 9.

I also have illustrated a shorter line including a despatch tube 11 and a return tube 13. Operating pressure is provided in these tubes by means of an exhauster 15 driven by an electric motor 17 which draws air from drum 19 connected by pipes 21 with the tubes. In the present embodiment of my invention the driving action of the electric motor 17 is governed in correlation with the movement of carriers in the tube lines.

For setting the governing mechanism in 65 operation when a carrier is despatched, I may provide suitable switches or circuit makers at the intake ends of the tubes and while they might be of any suitable kind, in the illustrated embodiment of the invention 70 these switches are automatic and adapted to be operated by the carrier when it is introduced. In Fig. 1 the position of these switches is indicated by the casings 23, 25, 27 and 29 in conjunction with the tubes 7, 9, 11 and 13, respectively. In Fig. 4 I have shown one suitable construction for such a switch. As there shown, it embodies a switch lever 31 pivoted on a shaft 33 and to which is attached spring 35 normally tending 80 to hold the switch open, free from contact 36 and with the end thereof projecting into the transit tube. The passage of the carrier by the switch will rock the lever against the force of the spring and close the 85 same on contact 36.

I preferably utilize similar switches in the casings 37, 39, 41 and 43 at or at a suitable distance from the delivery ends of 90 the transit tubes.

The operation of the motor 17 is governed by suitable mechanism here illustrated on panel board 45 shown at the lower right hand part of Fig. 1. An understanding of the operation of the particular installation 95 here shown as an example of my invention will be facilitated by a preliminary description of the specific mechanisms illustrated. I will therefore next describe such of these mechanisms as are utilized in governing the 100 longer transit line including the tubes 7 and 9.

The motor circuit may be opened and closed by means of a suitable, electrically-operated switch (lower left hand part of 105 panel board), the switch lever 47 herein forming the armature of a magnet 49. The construction of this switch will be best un-

derstood from Fig. 2. When the magnet 49 is energized, attracting the armature, the spring-pressed plunger 51 will engage contact 53 and connect the same through the 5 armature with binding post 55 through laminated copper strips 57. The switch lever or armature 47 is herein also provided with a downwardly extending arm 59 which carries (see Fig. 1) a bridge rod 61 which, 10 when the armature is attracted, connects the spring contact leaves 63 and 65, and a similar bridge rod 67 to connect leaves 69 and 71. In the present form of the invention the current is supplied to the motor while 15 the switch 47 is closed and therefore there is here provided a holding circuit therefor which might aptly be called a controlling circuit, since the continued action of the motor is dependent thereon. This holding 20 circuit may include a circuit closer in the form of a bridge 73 (see the upper right hand corner of the board 45) which normally connects contacts 75 and 76. Herein this circuit closer is lifted to break the circuit and I may provide for this purpose a 25 solenoid 77 to the core 79 of which the bridge 73 may be connected by means of a rod 81 carrying the bridge and secured to a transverse arm 83 connected at the top 30 of the core. These parts 81 and 83 are similar to the parts 161 and 165 shown in Fig. 3, but it should be noted that that figure does not represent the solenoid 77. The 35 solenoid 77 is operated by suitable means which herein includes a timed mechanism such as solenoid 85 the core of which in its upward travel operates against a dash pot 87 but which can descend freely. Connected to the core of this solenoid by an arm 40 89 and rod 91, similar again to the arm and rod 161 and 165 of Fig. 3, is a bridge 93 adapted when the solenoid or like timed device acts to connect contacts 95 and 97.

I shall next describe the circuits by which 45 the motor is governed in connection with the despatch of carriers through the tubes 7 and 9 by means of the installation here illustrated, disregarding the many variations that might be made therein within the 50 scope of my invention and reserving for the claims the broader statement of the essential principles underlying the same. We may assume that a carrier is introduced in tube 9 at the outer end thereof, at the upper 55 right hand corner of the sheet in Fig. 1. The carrier will engage the switch in casing 25, momentarily closing the same and will thereby energize magnet coil 49 and close the main controlling switch by means 60 of the following circuit:—positive line 99, wire 101, post 55, wire 103, post 105, wire 107, magnet coil 49, wire 109, the coil of a solenoid 111 hereinafter to be more fully referred to, wire 113, the switch at 25, wires 65 115 and 117, back to the intermediate line

119. The armature 47 will thus be attracted, completing the motor circuit as follows:—positive line 99, wire 101, post 55, armature 47, plunger 51, contact 53, wire 121, to the motor 17, thence by wire 123, to 70 negative line 125. Since the switch at 25 will immediately open when the carrier has passed it, I provide a suitable holding circuit for the magnet coil 49, which circuit starts from positive line 99, follows wire 75 101, post 55, wire 103, post 105, wire 107, magnet coil 49, wire 127 which may include a suitable resistance as shown, leaf contact 63, bridge rod 61, leaf contact 65, wire 129, contact 76, bridge or circuit closer 73, contact 75, wires 131 and 133 to intermediate line 119. This holding circuit will remain, continuing the energization of the motor until broken by the lifting of the contact maker 73 from contacts 75 and 76. 80 85

The breaking of this holding or controlling circuit is in the present instance effected by energization of the solenoid 77. Herein the circuit for this solenoid is controlled jointly by the switch adjacent the 90 delivery end of the tube, such as the switch 39, and by a timed circuit closer, herein the bridge 93 which completes the circuit between 95 and 97. The operation of the 95 timed moving means for this bridge, herein solenoid 85, may be controlled by the switch 47 already described. For example, the circuit may be as follows:—positive line 99, wire 101, post 55, wire 103, post 105, contact 69, bridge rod 67 and contact 71, thence 100 by wire 135 through the coil of solenoid 85, wire 137, to contact 139, bridge 141, contact 143, and wire 133 to the intermediate line 119. It will be apparent from tracing the 105 above circuit that after a carrier is introduced into a transit tube and the armature 47 is closed, the solenoid 85 will be energized and its core will commence to rise slowly against the dash pot 87 and, after a predetermined time sufficient to permit the 110 carrier to complete the major portion of its journey, the bridge 93 will connect contacts 95 and 97. The circuit for the solenoid 77 will not be complete, however, until the carrier has reached switch 39 at or near the end 115 of the tube. As this switch is thrown, the solenoid 77 will be energized by a circuit leading from positive line 99 through wire 138, coil of solenoid 77, wire 140, contact 95, bridge 93, contact 97, wire 142, switch at 39 120 and wire 117 to intermediate line 119, thereby lifting bridge 73 and breaking the holding circuit of the magnet coil 49, releasing the armature thereof and opening the motor circuit, thus causing the motor to stop. 125

We may suppose that after a carrier has been despatched in this manner and is part-way through the tube, it is desired to send another. It will be apparent that if the motor were stopped by the discharge of the 130

first carrier, as described, that the second might be stalled in the tube provided it were so far behind the first that the momentum of the motor and exhausteur would not be sufficient to effect its discharge. To prevent this means are provided for resetting the time device, such as the solenoid 85, the operation of which controls in part the breaking of the controlling circuit or holding circuit for magnet 49. This may be effected in any suitable manner on the despatch of the carrier, but in the present instance I have illustrated suitable relay means whereby it is effected immediately rather than directly by the movement of the switch lever at the intake end of the tube. Herein this relay takes the form of the solenoid 111 already referred to, the lifting of the core of which will act to raise bridge contact 141 from contacts 139 and 143. When the carrier is despatched, as for example at the intake end of tube 9, and the switch there is closed a circuit is completed which has already been traced. Beside energizing the coil of magnet 49, this circuit also energizes the coil of solenoid 111, thus lifting bridge 141. This bridge forms a part of the circuit for the coil 85 of the timing device. Thus, when each carrier is despatched this circuit is momentarily interrupted, the coil 85 is deenergized, its core drops freely in the dash pot and the timing device is reset. Thus, if two carriers are in the tube, although the first is discharged and closes the switch at 39, the stopping coil 77 will not be operated to interrupt the holding circuit by lifting of bridge 73, since the energizing circuit for the coil 77 will be open at 95 and 97. After the second carrier has completed the major portion of its journey, however, the reset timing device will have acted to close this break by means of the bridge 93, but the coil 77 will not act since the switch 39 has resumed its open position on the discharge of the first carrier. Operation of the motor will therefore continue until the second carrier has thrown this switch completing the energizing circuit of the coil 77, which will lift bridge 73, break the controlling circuit, deenergizing magnet 49, allowing armature 47 to fall open in the position shown in Fig. 2 and thus to interrupt the motor circuit.

I shall next describe the operation of the particular governing means here illustrated for controlling the passage of the carrier through the shorter line embodying tubes 11 and 13, disregarding as before the many variations that can be made therein within the scope of my invention and reserving the broader definition thereof for the claims. I shall also, in the beginning, disregard the longer tubes 7 and 9 as in describing them I have hitherto disregarded the shorter tubes 11 and 13. It will be understood that while

I have herein illustrated two lines of tubes and the mechanism adapted for use with the two in combination, that the means herein described for each set might be used alone to govern a single line.

70

In controlling the shorter line embodying the tubes 11 and 13, I make use of the mechanism shown in detail in Fig. 3 and comprising a solenoid 145 the core of which works in its upward course against dash pot 147 but which may fall freely. The dash pot, however, differs in its construction from the dash pot 87 in that the first portion of the upward travel of the core of solenoid 145 is not restricted thereby. For this purpose a relief valve 149 may be provided which, when the solenoid core is depressed, will be held open against the force of spring 151 by the piston of the dash pot resting thereagainst. When the coil 145 is energized, therefore, the core lifts quickly for a short distance and then commences its timed journey against the resistance of the dash pot in the usual manner, since the first portion of its lift will have permitted spring 151 to seat the valve 149.

75

Controlled by the solenoid 145 is a bridge 153 pressed by a spring 155 which tends to seat the same (see Fig. 1) on contacts 157 and 159. The bridge 153 is depressed against the action of the spring and held free of the contacts by means of a rod 161 connected by arm 165 to the solenoid core. Thus, when the solenoid is deenergized and the core drops to its lowest position as permitted by the action of the dash pot, the rod 161 will bear against bridge 153, and compressing spring 155, move the same free of contacts 157 and 159. When the solenoid is energized, however, the rapid initial rise thereof permitted by relief valve 149 will permit the spring immediately to seat the bridge 153 on the two contacts.

80

85

90

95

100

105

After the seating of the bridge as described, if the solenoid continues to be energized the core will rise slowly in the usual manner, the whole constituting a timed device. In the present embodiment of the invention this mechanism acts mechanically to open the circuit closer 73 and for this purpose the mechanism shown in Fig. 3 is placed directly under the solenoid 77 and its attendant mechanism as shown in Fig. 1, so that at the end of its travel the upper end of rod 161 will lift the bridge 73 free of contacts 75 and 76, thus breaking the controlling circuit which holds armature switch lever 47 closed and thus supplying current to the motor 17.

110

115

120

125

If a carrier is introduced, for example, at the terminal station end of tube 11 for despatch to the branch station, the switch 27 will cause energization of the magnet 49 and the solenoid 111 as already described with reference to switch 25. It will be noted that

130

wires from the switch 27 connect with the wires 113 and 117 referred to in the description of that circuit. Similarly, the holding circuit for the magnet coil 49 will be completed as before. However, this circuit is not controlled through the timing mechanism 85 as described for the long tube, but the motor continues in operation until the carrier passes the switch 41 which may be at 10 the extreme end of the line as shown or at a suitable distance therefrom. When this switch is closed a circuit is completed as follows:—positive line 99, wire 101, post 55, wire 103, contact 69, bridge 67, contact 71, 15 wire 135, wire 167, coil of solenoid 145, wire 169, contact 159, wire 171, switch at 41, wire 173, and return wire 117 to intermediate line 119. In this energization of the solenoid, the core thereof will quickly rise as permitted 20 by the relief valve 149 (see Fig. 3). The bridge 153 will snap into place under influence of the spring 155 joining contacts 157 and 159 and closing a holding circuit continuing the energization of the core of 25 this solenoid even after reopening of the switch at 41. This circuit is the same as the initial energizing circuit from the positive line through the coil 145 and to contact 159, but from there over bridge 153, to contact 30 157, wires 175 and 137, contact 139, bridge 141, contact 143 and wire 133 to the intermediate line 119.

The operation is as follows:—After a carrier is discharged from the tube the operation 35 of the motor will continue for a definite time controlled by a suitable timing device herein exemplified by the solenoid 145 and dash pot 147. When the predetermined time has elapsed the core of this solenoid approaching 40 the upper limit of its travel will engage the circuit closing bridge 73, lifting the same from contacts 75 and 76 and interrupting the holding circuit of magnet 49. If a second carrier is despatched after the 45 first but prior to the initiation of the operation of the timing device, the continued operation of the motor effected by the same after the discharge of the first carrier will be sufficient to insure discharge of the 50 second. If the second carrier is introduced after the action of the timing device the operation of solenoid 111 will break the holding circuit of the solenoid 145, since the latter includes the bridge 141, and the timing device will thus be reset.

If both lines of tubes as here shown are operated in conjunction and a carrier is passing through the shorter tube and another carrier is then introduced through the 60 longer tube, the solenoid 111, momentarily lifting bridge 141 as described, will release the timing device formed by the solenoid 145 and its dash pot and the carrier in the long line takes control and the operation is 65 as already described for that line, irrespec-

tive of the shorter line. Thus, there is no danger of the carrier being stalled in the longer line by the premature operation of the controlling mechanism designed for the shorter line.

In many instances in this document reference is made to the closing of a circuit, to the energization of a mechanism and the like. This has been done for clearness and definiteness of description. Obviously in 70 various instances the same effect might be produced by the opening of a circuit or the deenergization of a mechanism by changes within the skill of an electrician without departing from the spirit of my invention. 75

Having thus described the particular mechanism and the particular wiring thereof herein shown for the purpose of illustrating a specific embodiment of my invention, the principles exemplified thereby 80 which I consider new and desire to secure by Letters Patent I shall express in the following claims:—

1. Means for governing an electric mechanism in conjunction with the despatch of carriers through a transit tube or the like comprising a circuit closer controlling the energization of the mechanism, electric moving means therefor, a circuit for said means including a circuit closer and a switch 90 arranged to close on the delivery of a carrier, a timed moving device for said second mentioned circuit closer and means to initiate operation of the same on each despatch of a carrier.

2. Means for governing an electric mechanism in conjunction with the despatch of carriers through a transit tube or the like comprising an electrically operable switch, means for closing the same on the despatch 100 of a carrier, a holding circuit for the switch, an electrically-operated means controlling the energization thereof, a circuit for said last-mentioned means including a switch arranged to close on the delivery of a carrier and a circuit closer operated by timed mechanism having a controlling circuit completed by said electrically operated switch first mentioned and including a connection which is momentarily broken by the action 110 of the closing means aforesaid.

3. Means for governing an electric mechanism in conjunction with the despatch of carriers through a transit tube or the like comprising a switch, electro-magnetic means 120 to hold the same closed, means to energize the same on the despatch of a carrier and co-operating and complementary devices for deenergizing the same, one dependent in operation on the time elapsed since the despatch of a carrier and the other on distance traversed by a carrier.

4. Means for governing an electric mechanism in conjunction with the despatch of carriers through a transit tube or the like 125

comprising a switch, electro-magnetic means to hold the same closed, means to energize the same on despatch of a carrier, a circuit the completion of which effects deenergization of said electro-magnetic means, a connecting device in the circuit, a timed electric closing means therefor, a second connecting device in the circuit arranged for momentary closure by a carrier in passage, 10 a circuit for operating said closing means controlled by said switch and a connection therein momentarily broken by said energizing means aforesaid whereby to set the timed closing means.

15 5. Means for governing an electric mechanism in conjunction with the despatch of carriers through a transit tube or the like comprising a switch, electro-magnetic means to hold the same closed, means to energize

20 the same on despatch of a carrier, a circuit closer through which the energization of said means is maintained, an electrically moved device to open the circuit closer and deenergize said electro-magnetic means, a 25 connection arranged for momentary closure by a carrier in passage to set said electrically moved device in operation, a timing retarder therefor and means for resetting said device on despatch of a carrier.

30 6. Means for governing an electric mechanism in conjunction with the despatch of carriers through a transit tube or the like comprising a circuit closer controlling the energization of the mechanism, a timed 35 moving device for opening the same, means for starting the device including a switch arranged to close on the delivery of a carrier and means to reset the device on despatch of a carrier.

40 7. Means for governing an electric mechanism in conjunction with the despatch of carriers, through a transit tube or the like comprising an electrically operable switch, means for closing the same on the despatch 45 of a carrier, a holding circuit therefor, a circuit closer in said holding circuit, means to open the same, a timed moving means for the opening means and means for setting the moving means in operation comprising 50 an operating circuit which is momentarily broken by the action of the closing means aforesaid and which includes a switch adjacent the delivery end of the tube.

8. Means for governing an electric mechanism in conjunction with the despatch of carriers through a transit tube or the like comprising a circuit closer controlling the energization thereof, a member for opening the same, an electric coil for moving said 55 member, a dash pot for retarding such movement having a relief valve permitting free initial movement, a connecting device held open by said member and arranged to seat after such initial movement, means to energize said coil comprising a switch operated

by passage of a carrier in the tube and a circuit continuing the energization thereof leading through said connecting means.

9. Means for governing an electric mechanism in conjunction with the despatch of carriers through a transit tube or the like comprising a circuit closer controlling the energization thereof, a member for opening the same, an electric coil for moving said member, a connecting device held open by 70 said member and arranged to seat at an intermediate phase of the movement of said member under the action of said coil, retarding means for the member effective after the seating of said device, means to energize 75 said coil comprising a switch operated by passage of a carrier in the tube, and a circuit continuing the energization thereof leading through said connecting means.

10. Means for governing an electric mechanism in conjunction with the despatch of carriers through transit tubes or the like of different lengths comprising a circuit controlling the energization of the mechanism, means for opening the controlling circuit having an operating circuit including a switch at the delivery end of a long tube and a timed circuit-closing device adapted to be reset on each despatch of a carrier through said long tube, other means for 95 opening the controlling circuit including a timed device, means for setting the same in operation on delivery of a carrier from a short tube and an operating circuit therefor arranged to be broken on the despatch of a 100 carrier through either tube.

11. Means for governing an electric mechanism in conjunction with the despatch of carriers through transit tubes or the like of different lengths comprising a circuit controlling the energization of the mechanism, means for completing the same on the despatch of a carrier, coöperating and complementary timing and carrier controlled devices in conjunction with a long tube for 105 opening the controlling circuit, a timing device set in operation by the passage of a carrier in a short tube for opening the controlling circuit and means effective on introduction of a carrier in the long tube to 110 stop the operation of said second mentioned timing device.

12. Means for governing an electric mechanism in conjunction with the despatch of carriers through transit tubes or the like of different lengths comprising a circuit controlling the energization of the mechanism, means for completing the same on the despatch of a carrier, coöperating and complementary timing and carrier controlled devices in conjunction with a long tube for 120 opening the controlling circuit, a timing device set in operation by the passage of a carrier in a short tube for opening the controlling circuit and means effective on 125 130

introduction of a carrier in either tube to set back said second mentioned timing device.

13. Means for governing an electric mechanism in conjunction with the despatch of carriers through transit tubes or the like of different lengths comprising an electrically operable switch, means for closing the same on despatch of a carrier, a holding circuit therefor, means for breaking said holding circuit having an operating circuit including a switch at the delivery end of a long tube and a circuit closing device controlled by a timed device having an energizing circuit controlled by said switch, other means for breaking said holding circuit including a timed device, an energizing circuit for setting the same in operation on the delivery of a carrier from a short tube, a connection common to the energizing circuits of said timed devices arranged to be opened on each despatch of the carrier.

14. Means for governing an electric mechanism in conjunction with the despatch of carriers through transit tubes or the like of different lengths comprising a controlling device placed in action on each despatch of a carrier in either tube, and means for dis-

establishing the action of said device comprising timing mechanism having its operation initiated by the despatch of a carrier in a long tube and other means for disestablishing the action of said device comprising a timing mechanism having its operation initiated by the approach of a carrier to delivery in a short tube.

15. Means for governing an electric mechanism in conjunction with the despatch of carriers through transit tubes or the like of different lengths comprising a controlling device placed in action on each despatch or a carrier in either tube, and means for disestablishing the action of said device comprising timing mechanism having its operation initiated by the despatch of a carrier in a long tube and other means comprising a timing mechanism having its operation initiated by the approach of a carrier to delivery in a short tube, and means whereby initiation of operation of said first mechanism discontinues the operation of the second.

In testimony whereof I have signed my name to this specification.

JAMES G. MACLAREN.
